INVENTOR

UNITED STATES PATENT OFFICE

ALAN R. HART, OF SYRACUSE, NEW YORK

SCORE PAD OR MEMORANDUM HOLDER

Application filed September 28, 1931. Serial No. 565,610.

This invention relates to a new and improved score pad or memorandum holder.

Although my device may be used in various ways, it is particularly well adapted to hold 5 a pad which is used in keeping the score of card games, such as auction or contract bridge.

Although it is more convenient to have the score card on the card table top when scoring is being done, it will, if left in that position, interfere to some extent with the easy actual play of the game, and the main object of my invention is to provide a score card holder which may be easily placed on the 10 table top when scores are recorded, but which may then be easily removed from the table top and held in a convenient place until it is again desired to record the score.

Another object is to provide a device of the 20 character described which may be easily removed from the table when no game is being played, and it is desired to fold the table and remove it to a place of storage.

Other objects and advantages relate to the 25 size, shape and arrangement of parts, all as will more fully appear from the following description taken in connection with the accompanying drawing, in which:—

Figure 1 is a perspective view of my device 30 showing the same in position on a table top adjacent one corner thereof.

Figure 2 is a section on line 2—2 of Figure 1.

Figure 3 is a perspective view of the pad 35 holder portion of my device.

Figure 4 is a perspective view of the member in which the part shown in Figure 3 is suspended.

Figure 5 is a perspective view of the strap 40 by means of which the device is secured to a table.

My device comprises an elongated suspending member 1 which has a top portion 2 provided with an elongated slot 3.

The top portion 2 forms a right-angle 45 with the rear depending portion 4.

The pad holding member 5 comprises a flat body 6, the length of which is such that it may be received in the slot 3 of member 1.

Adjacent the lower end of member 5 and

extending partially of the length thereof, is a struck-out elongated tongue 7 between which and the main portion 6, may be received the lower edge of a scoring or memorandum pad 8.

The upper edge of the tongue 7 is bent inwardly to a slight degree for a purpose hereinafter to be explained.

The upper edge of the member 5 is return bent to form a rib 9 which extends outwardly from one face of the member 5 and a second opposed rib 10 which extends outwardly from the opposite face of member 5.

The distance between the outer edges of ribs 9 and 10 is greater than the width of slot 3 so that when the member 5 is inserted in slot 3, it will be held suspended in the member 1.

Beneath the rib 10 is a depending tongue 11 which is in spaced relation to the main 70 body 6 so that the upper edge of a score or memorandum pad may be received therebetween.

The lower edge of member 5 is rolled upon itself, as shown at —a—, to form a tubular 75 portion in which a pencil 12 may be retained.

The diameter of such tubular portion is greater than the width of the slot 3 so that the member 5 cannot be removed from the member 1, but may be moved relatively thereto. The tubular portion is also positioned wholly at the rear of member 5 so that when member 5 is in the raised position it may move angularly in relation to member 1 to lie flat on table 16.

For the purpose of providing a convenient means by which my device may be secured to a table, I provide an elongated strap 13 having offset perforated ends 14 and 15 so that the strap 13 may be secured in position on the 90 edge of a table 16 as by screws 17, with the main portion of strap 13 in spaced relation to the edge of the table 16.

When the member 5 has been assembled in the member 1, and it is desired to secure the same to the table 16, the depending portion 4 of member 1 is placed in position between the strap 13 and the edge of the table 16, and the device will then be held securely in position 95 on the table 16.

100

It will be understood that before the device is ready for use, a score or memorandum pad 8 will have been placed in position on member 5 with its upper edge secured by tongue 11, 5 and with its lower edge secured by tongue 7.

When it is desired to record scores or memoranda, the member 5 is raised upwardly through slot 3 and is then turned downwardly on to the surface of the table 16 and in the 10 position shown in heavy lines in Figures 1 and 2.

After the score or memorandum has been recorded, the member 5 is raised and allowed to drop downwardly in the member 1 into the 15 position shown in dotted lines on Figures 1 and 2.

In this latter position, the device forms no obstruction for the upper surface of the table 16.

20 As above described, the upper edge of the tongue 7 is bent slightly inwardly, and this is also true of the lower edge of the tongue 11.

The purpose of so forming tongues 7 and 11 is so that there may be no possibility of such 25 tongues catching on the edges of the slot 3 when the member 5 is moved therein, and to facilitate such movement, I also prefer to have the outer edge of the slot 3 beveled as indicated at —b— on Figure 2.

30 So that the sheets from the pad 8 may be easily removed as the same are filled with indicia, and also so that there may be no possibility of the pad 8 becoming loosened, with respect to tongues 7 and 11, I prefer to have pad 8 scored at —c— and —d— adjacent the edges of the tongues 7 and 11.

The different parts of my device may be made of metal or other appropriate material, and the size of the same may be varied to accommodate different sizes of score or memorandum pads for it will be understood that although I have here shown and described a specific structure and form and relation of the parts thereof as an exemplification of an 40 embodiment of my invention, I do not desire to restrict myself to the exact size, shape or relation of parts, as various changes may be made within the scope of the appended claims.

45 50 I claim:

1. In a device of the class described, a frame having a horizontal portion provided with an elongated slot and a vertical portion adapted to be removably mounted on a support 55 and a pad-holder comprising a substantially flat rectangular body member slidably mounted in said slot from a horizontal position above the frame to a vertical suspended position in the frame, and opposed spaced tongue members made integral with said body and adapted to releasably clamp a score pad thereon.

60 65 2. In a device of the class described, a frame adapted to be removably mounted on a support and comprising a portion having

an elongated slot adapted to extend outwardly from said support and a pad-holder comprising a substantially flat rectangular body member mounted in said slot for movement therethrough, said body having one side bent 70 upon itself to form a laterally projecting rib of greater width than said slot for limiting the movement of the holder in the slot, and opposed spaced tongue members made integral with said body adapted to releasably 75 clamp a score pad thereon.

3. In a device of the class described, a frame adapted to be removably mounted on a support and comprising a portion having an elongated slot adapted to extend outwardly from said support and a pad-holder comprising a substantially flat rectangular body member mounted in said slot for movement therethrough, said body having one side bent 80 upon itself to form a laterally projecting rib of greater width than said slot, and a tongue member extending inwardly from said rib and spaced from the body to removably maintain a score pad thereon.

4. In a device of the class described, a frame adapted to be removably mounted on a support and comprising a portion having an elongated slot adapted to extend outwardly from said support and a pad-holder comprising a substantially flat rectangular body member mounted in said slot for movement therethrough, said body having opposed sides bent to form laterally projecting ribs of greater width than said slot for preventing the removal of the holder from the frame, and opposed spaced tongue members made integral with said body intermediate said ribs, adapted to releasably clamp a score pad 90 thereon.

5. In a device of the class described, the combination with a table, of a frame adapted to be removably secured to the table in a plane below the top thereof and a pad-holding member slidably supported by the frame for movement from a horizontal position resting on the top of the table to a vertical suspended position at one side of the table.

6. In a device of the class described, the combination with a table, of a frame adapted to be removably secured to the table in a plane below the top thereof and having a portion provided with an elongated slot adapted to extend outwardly from the table and a pad-holder comprising a substantially flat rectangular body member mounted in the slot for movement therethrough from a horizontal position resting on top of the table to a vertical suspended position at one side of the table, and means associated with the body member for limiting the movement of the holder in said slot.

In witness whereof I have hereunto set my hand this 21 day of September, 1931.
